Fig. 6 5 -

The diagram shows a circular pattern with concentric rings. The outermost ring is labeled '39' at the top and '39b' at the bottom. The next ring in is labeled '40' at the top and '41' at the bottom. The inner ring is labeled '42' at the top and '43' at the bottom. There are several small, irregularly shaped hatched areas within the rings, particularly in the inner and middle sections. A horizontal line with an arrow pointing to the left is labeled '5' at its left end. The label 'Fig. 7' is located in the bottom left corner of the diagram area.

MILLING MACHINE INDICATING DIAL

Lester F. Nenninger and Fred A. Hassman, Cincinnati, Ohio, assignors to The Cincinnati Milling Machine Co., Cincinnati, Ohio, a corporation of Ohio

Application December 30, 1943, Serial No. 516,296

8 Claims. (Cl. 90—21)

1

This invention relates to machine tools and is particularly related to improvements in dial indicating mechanism for a milling machine.

It is an object of this invention to improve the convenience of operating and controlling a milling machine.

It is also an object of this invention to provide in a machine tool having a plurality of operating positions, an improved indicating dial mechanism associated with the control devices which may be readily observed by the machine operator while in the same operating position from which he watches the cutting operation being performed on the work piece by the machine.

Another object is to provide a common dial indicating mechanism for a milling machine, actuated by operating control mechanism at the front of the machine and by duplicate operating control mechanism at the rear which may be readily observed by the operator from either of these operating positions from which he also observes the cutting action of work and tool in the machine.

Another object of this invention is to provide an improved feed rate determining mechanism for a milling machine which is suitable and convenient for a multiple control position machine.

An additional object of this invention is to provide an improved single feed rate dial mechanism for milling machine which is observable from opposite sides of the machine, but which will indicate the same rate readings from either side and without duplicating parts in the mechanism.

And still another object of this invention is to provide an improved dial indicating mechanism for a milling machine having the feed box and associated rate change mechanism mounted in the knee and having a dial so positioned on the knee that it may be actuated from the rate change mechanism and operable from a plurality of control stations for the rate change mechanism located on opposite sides of the dial indicating mechanism, the dial being readable from either side of the machine to determine the feed rate changes effected.

Other objects and advantages of the present invention should be readily apparent by reference to the following specification, considered in conjunction with the accompanying drawings forming a part thereof and it is to be understood that any modifications may be made in the exact structural details there shown and described, within the scope of the appended claims, with-

2

out departing from or exceeding the spirit of the invention.

Referring to the drawings in which like reference numerals indicate like or similar parts:

5 Figure 1 is a left side elevation of a knee and column type milling machine embodying the features of this invention.

10 Figure 2 is an enlarged fragmentary left side elevation of the knee, saddle, and table of the milling machine shown in Figure 1, as indicated by the line 2—2 in Figure 4.

Figure 3 is a diagrammatic showing of the operating and control mechanism and indicating dial of the milling machine of Figures 1 and 2.

15 Figure 4 is a fragmentary plan view partly in section of the milling machine on the line 4-4 of Figures 1 and 2.

Figure 5 is a fragmentary section on the line 5-5 of Figures 2, 4, 6, and 7.

20 Figure 6 is an enlarged face view of the rotating indicating dial shown in Figure 5.

Figure 7 is an outside view of the indicating window cover for the rotating dial shown in Figures 5 and 6.

25 Figure 8 is an enlarged fragmentary view of a portion of the indicating window cover of Figure 7 showing one form of indicating window.

Figure 9 is an enlarged fragmentary view of 30 a portion of the indicating window cover of Figure 7 showing another form of indicating window.

As illustrative of a machine tool incorporating the features of this invention, there is illustrated a knee and column type milling machine, Figure

35 1, having a base 1 and the usual upright integral column 2 which carries a rotatable cutter spindle 3.

A knee 4 is mounted for vertical motion on appropriate guideways 5 formed on the column

2. On top of the knee 4 on appropriate guideways 6 is slidably mounted the saddle 7 on top of which on suitable guideways 8 is slidably mounted the work table 9.

In the operation of such a machine tool of the character of a knee and column type milling 45 machine, the operator controls the machine while standing in the normal operating position at the front of the knee and work table. It is also desirable for the operator to stand in a rear operating position behind the work table and

50 adjacent the left side of the column in order to properly observe the cutting action of the cutter on the work piece. Operating controls are provided at the front of the knee for manipulation by the operator when at the front of the machine

55 and a duplicate set of rear operating controls are

provided when operating the machine from behind the work table.

An operating position provided at the front of the machine, designated by the reference character A, Figures 1, 2, and 4, has associated therewith a control device or lever 10 mounted on the knee 4 by any suitable means 10a operatively connected to the feed change mechanism which may be manipulated by the operator to select desired rates of feed movement for the knee, saddle, and table. Also, when the operator is in the rear operating position designated by the reference character B, he may manipulate a rear control device or lever 11, appropriately mounted by suitable means 11a on the rear of the knee 4. These control levers 10 and 11 may be connected to the feed rate control mechanism for the knee, saddle, and table, such as is illustrated in Figure 3 wherein is shown diagrammatically a change feed transmission, designated generally at 12, which has a series of shiftable change gears for effecting different rates of feeding movement in the work carrying members 4, 7, and 9. These feed changes are effected by power by rotating the gear shifting cam drums 13 which, through appropriate shifter arms 14 effect the feed changes in the feed box or change feed transmission 12. These cam drums 13 may be driven from any source of power, usually the main driving motor or prime mover for the machine, which actuates a power shaft 15. This shaft 15 may be reversibly connected through the reversing bevel gear mechanism 16, 17 and 18 and the reversing clutch 19 to a drive shaft 20 to which is connected, through gearing 21, 22, and 23, the gear shifting cam drums 13 for rotation thereof in one direction or the other to effect the feed changes. The reversing clutch 19 may be actuated by any suitable shifter yoke 24 carried on a shifter rod 25, one end of which may be connected to the control handle 10 at the front of the machine and the other end of which may be appropriately connected to the control handle 11 at the rear of the knee as shown in Figure 3. Thus, manipulation of either the lever 10 or the lever 11 will cause the desired changes in the feed change transmission 12 to determine the rate of operation of the work carrying members 4, 7, and 9.

Associated with this feed change mechanism is an indicating dial designated generally at 26 which comprises a rotatable conical figure dial 27, Figures 5 and 6, which is fixed to a shaft 28, appropriately journaled in a suitable bearing 29 against axial movement in the knee 4. On the inner end of this shaft 28 is fixed a spiral gear 30 which is driven by mating spiral gear 31 carried on a shaft 32 journaled in the knee 4. The shaft 32, in turn, has a gear 33 driven by a gear 34 formed integral with the driving gear 22 for the feed changing cam drums 13 so that when the cam drums 13 are driven to effect feed changes in the transmission 12 the indicating dial 27 will be rotated to appropriate positions to indicate the position to which the feed box or change feed transmission 12 has been adjusted and therefore the rate of operation of the knee, saddle, and table as determined by the control levers 10 or 11.

It is to be particularly noted, Figures 1 and 2, that the indicating dial 26 is located on the left side of the knee 4 in a position intermediate of the operator's position A at the front of the machine and position B at the rear and intermediate the corresponding control levers 10 and 11. It can, therefore, be seen that by this arrangement the operator, when standing in the front oper-

ating position A, may read the dial 26 in the direction indicated by the arrow 35 and can direct his attention while in the same position in the general direction 35a to watch the work table 9 and work being machined thereon. It will be further noted that when the operator is in the rear position B he can also observe the dial 26 in the direction indicated by the arrow 36 and can direct his attention in the general direction 36a of the work table 9.

In order that the dial 26 may be read from the two different positions A and B, it is provided with a double array of figures, one of which group may be read from the front position A and the second group which may be read from the rear operating position B. This arrangement of figures is best shown in Figure 6 and comprises a group of figures marked 37 peripherally spaced about the conical surface 27a of the dial 27 in such a way as to be read when the operator stands at position A. A second group of figures 38 is also provided on the surface 27a of the dial 27 but facing in the opposite direction and appropriately offset from the figures 37 so that they may be readily observed and read by the operator when standing in the rear control position B.

Covering the entire dial 27 is the indicating window cover 39 fixed by means of a collar 39a and screws 39b to the knee 4 and having a pair of indicating windows 40 and 41 formed therein, Figures 7 and 8, which are elongated so as to respectively expose the figure indicating the actual conditions selected and the selections of increasing or decreasing feed rates next obtainable by rotation of the dial 27. Indicating pointers 42 may be provided intermediate the length of each of the indicating windows 40 or 41 so as to more accurately show the exact feed rate being obtained. It may also be desirable to show just the actual reading of the feed being effected in which case the arrangement shown in Figure 9 may be utilized in which a relatively small window 41a is provided which only exposes one indicating figure at a time. Thus, when the operator stands in the front position A he may observe the various figures as indicated through the indicating window 40 and when standing in the rear position he will observe the figures indicated in the window 41, Figure 7. In this way a common indicating dial, operable by control devices from a plurality of operating positions at the front and at the rear of the machine, is provided having a plurality of sets of indicating figures for each of the operating positions from which the control devices are actuated by the operator while watching the indicating dial. The dial is so arranged relative to the operating positions that constant vigilance of the work and cutter during the machining operation may be readily had from any operating position of the machine.

What is claimed is:

1. In a milling machine, a column, a knee, saddle, and table mounted on said column to effect relative movement of work and cutter in said machine, power feed change mechanism in said knee controlled from a front and rear operating position of the knee for effecting feed rate changes in said knee, saddle, and table, comprising a control lever on the front of said knee for rendering said power feed change mechanism operable or inoperable, a duplicate rear control lever on said knee for similarly effecting said power feed change mechanism, and a common rate indicating dial driven by said power feed changing means and mounted on said knee in-

5

termediate said control levers, said dial having a projecting conical surface for carrying the rate indications and rendering them observable by the operator from either operating position.

2. In a milling machine, a column, a knee, saddle, and table mounted on said column for relative movement of work and cutter in said machine, power means for making feed changes in said knee, saddle, and table, control means for said power means at a front and rear operating position of the machine comprising a control lever on the front of said knee for rendering said power feed changing mechanism operable or inoperative, a duplicate rear control lever on said knee for similarly controlling said power feed change mechanism, a common indicating dial driven by said power feed changing mechanism having two independent arrays of indicating figures thereon, one group observable by the operator from the front operating position of the machine and the other group facing in the opposite direction observable by the operator when in the rear operating position, said indicating dial being so positioned as to permit the operator when in either of said operating positions of the machine to observe said dial and direct his attention to the cutting action of the work and cutter of the machine.

3. In a milling machine, a column, a cutter spindle mounted in said column, a knee, saddle, and table carried on said column for relative movement of table and cutter spindle, means for actuating said knee, saddle, and table at variable feed rates including a change feed transmission in said knee, power operated means for effecting rate changes in said transmission, control means for said power rate changing means comprising means for rendering said power means operative or inoperative, a control lever operably connected to said last-mentioned means located on the front of said knee, a duplicate control lever operably connected to said last-mentioned means positioned on the rear of said knee, a feed rate indicating dial mounted on said knee intermediate of said levers and driven by said power feed changing means, said dial having a frusto-conical surface carrying rate indications thereon for observations from either station by the operator when manipulating either of said control levers.

4. In a milling machine having knee, saddle, and table members, change feed transmission in said knee for actuating said members at various feed rates, power means for making rate changes in said transmission, a control lever on the front of said knee for controlling the operation of said power means, a similar control lever on the rear of said knee, an indicating dial driven from said power means located on said knee intermediate said levers, duplicate series of indicia on said dial, one series observable by the operator when manipulating one of said control levers and the other series observable when manipulating the other lever, said series being disposed in oppositely facing relationship on said dial, and dual indicating reference points on said knee associated with both of said series of indicia for showing the feed rates selected.

5. In a machine tool member containing a variable feed transmission and a power operable rate change mechanism therefor, the combination with a feed rate dial rotatably mounted on said member and connected for rotation by said mechanism, of control levers spaced on opposite sides of said dial for controlling power operation

6

of said mechanism, said dial having portions facing each of said levers, fixed indicators adjacent each portion, said dial having one set of indicia cooperable with one of said indicators and readable from one station and a second set of indicia cooperable with the other indicator and readable from the second station, and means blanking out the set of indicia that is unreadable as respects a given station.

5 6. In a knee and column type milling machine having a variable feed transmission and a power operable rate change mechanism contained in the knee, the combination of control levers mounted in spaced relation on the knee at different machine operating stations for controlling power operation of said mechanism and thereby progressive changes in the rate of said transmission, a single dial mounted on the knee between said levers for rotation by said mechanism and having two sets of similar rate indicia thereon, said sets being oppositely arranged and circumferentially displaced so that one set is readable from one station and the other set is readable from the other station, and both sets give the same reading from each station for a given position of the dial.

10 7. In a machine tool having a member translatable by a variable feed transmission contained therein and a rate change mechanism for changing the rate of said transmission, the combination with a pair of spaced levers mounted on said member at different control stations for selectively controlling operation of said mechanism, of a rate dial intermediately located with respect to said levers and operable by said mechanism, a housing enclosing said dial and having windows annularly and axially spaced therein, and two sets of rate indicia carried by said dial, and so arranged that one set is readable through one window from one station and the other set is readable through the other window from the other station.

15 8. In a machine tool having a support, a work table traversably mounted on said support, and a variable feed transmission including a power operable rate change mechanism mounted in the support for actuating the table, the combination with a pair of control levers mounted on the support at control stations located on opposite sides of said table, of means operably connecting said levers for controlling power operation of said mechanism, and a common means including a dial driven from said mechanism and located on said support beneath said table and between said levers for indicating progressive changes made in the rate setting of said mechanism, caused by operation of a lever, said dial having two sets of rate indicia respectively readable from the different stations whereby the operator may selectively utilize either station for changing the rate of operation and observing the changes as made.
